(57) CLAIM

The ornamental design for a small cell for mounting on a light pole, as shown and described.

DESCRIPTION

FIG. 1 is a perspective view of a small cell for mounting on a light pole showing a first embodiment of our new design.

FIG. 2 is a top plan view thereof.

FIG. 3 is a bottom plan view thereof.

FIG. 4 is an enlarged scale partial cross-sectional view thereof taken along line 36-36 of FIG. 3.

FIG. 5 is a front elevational view thereof.

FIG. 6 is a rear elevational view thereof.

FIG. 7 is a left side elevational view thereof.

FIG. 8 is a right side elevational view thereof.

FIG. 9 is a perspective view of a small cell for mounting on a light pole showing a second embodiment of our new design.

FIG. 10 is a top plan view thereof.

FIG. 11 is a bottom plan view thereof.

FIG. 12 is an enlarged scale partial cross-sectional view thereof taken along line 12-12 of FIG. 11.

FIG. 13 is a front elevational view thereof.

FIG. 14 is a rear elevational view thereof.

FIG. 15 is a left side elevational view thereof.

FIG. 16 is a right side elevational view thereof.

FIG. 17 is a perspective view of a small cell for mounting on a light pole showing a third embodiment of our new design.

FIG. 18 is a top plan view thereof.

FIG. 19 is a bottom plan view thereof.

FIG. 20 is an enlarged scale partial cross-sectional view thereof taken along line 20-20 of FIG. 19.

FIG. 21 is a front elevational view thereof.

FIG. 22 is a rear elevational view thereof.

FIG. 23 is a left side elevational view thereof.

FIG. 24 is a right side elevational view thereof.

FIG. 25 is a perspective view of a small cell for mounting on a light pole showing a fourth embodiment of our new design.

FIG. 26 is a top plan view thereof.

FIG. 27 is a bottom plan view thereof.

FIG. 28 is an enlarged scale partial cross-sectional view thereof taken along line 28-28 of FIG. 27.

FIG. 29 is a front elevational view thereof.

FIG. 30 is a rear elevational view thereof.

FIG. 31 is a left side elevational view thereof; and,

FIG. 32 is a right side elevational view thereof.

The dot-dash broken lines in FIGS. 3, 11, 19 and 27 define the boundary of the claim, which extends to the boundary but does not include the boundary, while all other broken lines depict portions of the small cell for mounting on a light pole that form no part of the claimed design.
